DITCHING AND GRADING SCRAPER.

No. 376,022.

Patented Jan. 3, 1888.

UNITED STATES PATENT OFFICE.

LUCIUS E. ASHLEY, OF STOCKTON, CALIFORNIA, ASSIGNOR OF ONE-HALF TO
ASA CLARK, OF SAME PLACE.

DITCHING AND GRADING SCRAPER.

SPECIFICATION forming part of Letters Patent No. 376,022, dated January 3, 1888.

Application filed July 5, 1887. Serial No. 243,460. (No model.)

To all whom it may concern:

Be it known that I, LUCIUS E. ASHLEY, a citizen of the United States, residing at Stockton, in the county of San Joaquin, State of California, have invented certain new and useful Improvements in Ditching and Grading Scrapers, of which the following is a specification, reference being had therein to the accompanying drawings.

10 My invention relates to certain improvements in scrapers which are mounted upon wheels and drawn by cattle or horses, and used in making and leveling roads, excavating ditches, canals, and cellars, and generally in 15 raising and removing loosened soil or gravel to a short distance.

It consists in the manner of hanging the iron or steel bottom to the vehicle and controlling its position, as well as the position of 20 the wheels, by a suitable system of levers; also in such other devices as will be hereinafter described, and pointed out in the claims.

To more fully explain my invention reference is had to the accompanying drawings, in 25 which—

Figure 1 is a left-hand side elevation showing my invention complete. Fig. 2 is a plan of the same without the levers. Fig. 3 is a section through line $\alpha\alpha$ of Fig. 2, showing the 30 raising and lowering lever. Fig. 4 is a sectional view showing the carrying-wheels set at an incline. Fig. 5 is a detached view of the raising and lowering lever.

Similar letters of reference indicate corresponding parts.

35 A is the main frame of the vehicular portion of the scraper, and has attached to it at one side by connecting-bars a an operator's platform, A'.

40 B represent the convexed wheels, which are shown in Figs. 1 and 2 in an exact vertical position and in Fig. 4 in a slightly inclined position.

B' represents the axles, attached by king-pins B³ to the body A. Yokes B² are attached to the 45 axles and are above the body A, the king-pins B³ connecting them and the axles and the body A together, and serve as guides to the lateral movements of the axles for the purpose of controlling the course of the scraper when in action. The draft attachment at the front of

the scraper is composed of a draft rod and clevis, C, and a guide, c. The rod C is loosely attached to the body A by a pin immediately in front of the forward axle. The guide c is a transverse iron arch at the front of the body 55 A, which permits of the free action of the rod C at any angle horizontally to the line of the body A. The scraper blade or shoe D may be of iron or steel or an iron-shod board, and is attached at its front to the body A by a 60 hinge, d e e, the head d being attached to the blade and the straps e e to the surface of the body A, the three parts being provided with eyes connected together by a cross-pin. A bar, E, is riveted to the blade D just behind 65 the hinge just described, and impinges upon a lug, E', attached beneath the body A, and serves the purpose of steadyng the blade D in a suitable working position.

The rear of the blade D is attached to the body 70 A by diagonal braces f g and right-angle brace i, forming a right-angle triangle, of which the body A is the base and the blade D is the hypotenuse. The inner ends of the braces f, g, and i are furnished with eyes and engage with 75 the eyes of straps h h, attached to body A by means of a cross-pin.

A lever, F', for raising or lowering the blade D has a hook-shaped end which engages with the brace i, and has within the hook a roller, 80 l, to prevent friction and to facilitate the raising and lowering movements when the pressure of the weight of the blade is greatest upon the brace i. An L-shaped iron strap, F, is bolted to the surface of the body A and 85 extends outwardly parallel with the brace i, and has at its outer end an iron circle, K, bolted thereto, which engages with a guide, F², upon the lever F'.

In order to raise the blade D to deposit its 90 load, the lever F' is thrown to the left-hand side of the scraper, and to lower it into working position again the lever F' is reversed, the guide F² engaging with the circle K upon the iron F, maintaining it in a steady position.

When traversing uneven grades, I am enabled to change the course of the scraper without deviating the team by means of vertical levers H H, which are attached to the axles by means of connecting-rods b b. The fulcrums 95 100

of these levers are upon a yoke, G, bolted rigidly to the body A. The levers are furnished with spring-detents engaging with perforated segments of circles I, which are attached to the ends of yoke G. Dotted lines, in connection with the rear wheels, B, of Fig. 2, illustrate the feature of my invention, and show what may be the relative position of the wheels and axles when controlled by levers H. 5

10 The blade D is convexly formed in order to present a holding-surface to the earth at its front. The wheels B, being convex, present a holding-edge to the soil capable of resistance to side draft, and by being inclined, as shown 15 in Fig. 4, still further resist, as required, the side-draft pressure resulting from the relative position at times of the body A to the team when the blade D is presented obliquely to the line of its draft.

20 I am aware that it is not new to attach a blade or shoe to a frame and mount the same upon wheels, neither is it new to set said blade obliquely to the frame; but

25 What I claim as new and of my invention is—

1. The vehicle-body A, the wheels B, the axles B', and the blade D, suitably attached to the body A, in combination with the lever F', and the braces f g i, the lever F', engaging with brace i and being provided with the guide F², engaging with the circle K of the iron F, attached to body A, all substantially as and for the purpose set forth.

2. The combination, substantially as described, of the body A, the platform A' a a, the axles B', the yoke B², the king-pin B³, and the draft apparatus consisting of the rod C and the transverse yoke c.

3. The combination, substantially as described, of the vehicle A A' a B B' B² B³, the blade D, set obliquely to the body A, and having the bar E engaging with the lug E', attached beneath the body A, the connecting-braces f

g i, the latter being at right angles to the body A, the body A, the brace i, blade D, forming a right-angled triangle, the lever F' provided with the roller l, and the J-shaped iron F, provided with the circle K, engaging with the guide F² of the lever F'. 45

4. The combination, substantially as described, of the vehicle, the blade D, the yoke G, attached to body A and provided with perforated circles I, the guiding-levers H b, attached to axles B' and adapted to control the direction of the body A, and the draft attachment consisting of the rod C and transverse arch c. 50

5. A scraper-frame suitably mounted upon axles and wheels, such wheels being convexly formed and inclining upon the axles, in combination with a scraping-blade set obliquely to the body A, a suitable draft attachment, and suitable levers for raising and lowering the blade and for directing the course of the scraper by changing the position of the axles 55 and wheels irrespective of the course of the team.

6. The combination, with the body A, suitably mounted and provided with the blade D, connected thereto by the brace i, of the J-shaped iron F, provided with the circle K, engaging with the guide F² upon the lever F', substantially as set forth. 70

7. The combination, substantially as described, of the body A, the platform A', the straps a, and the draft attachment C c. 75

8. The combination, substantially as described, of the body A, the convex wheels B, the axles B', the yokes B², and the king-pins B³. 80

In testimony whereof I affix my signature in the presence of two witnesses.

LUCIUS E. ASHLEY.
